UNITED STATES PATENT OFFICE.

ABRAHAM L. FREEDLANDER, OF DAYTON, OHIO, ASSIGNOR, BY DIRECT AND MESNE ASSIGNMENTS, OF THREE-FOURTHS TO THE DAYTON RUBBER MANUFACTURING COMPANY, OF DAYTON, OHIO, A CORPORATION OF OHIO, AND ONE-FOURTH TO GENERAL MOTORS RESEARCH COMPANY, OF DAYTON, OHIO, A CORPORATION OF DELAWARE.

DRIVING BELT.

Application filed June 14, 1922. Serial No. 568,155.

This invention embraces an improved driving belt, designed particularly as a fan belt for use in automobiles, and a method of manufacturing or producing such a belt.

5 That branch of my invention which is embodied in the article or belt consists, essentially, of a belt comprised of a plurality of circumferential members—an inner or compression member, an intermediate or central member and an outer or tension member, each member being fabricated in this wise:

10 The compression member composed of soft rubber mixed with cotton, wool or other fiber, the fibers preferably running crosswise and 15 vulcanized.

15 The central member composed of rubberized cord fabric cut straight or parallel to the cords and in a pre-stretched condition, due to having been materially stretched before being 20 combined with the other members.

The tension member composed of rubberized fabric cut on the bias or at an angle.

25 This results in the completed belt being substantially non-stretchable. As these fabric elements are of different characteristics and as each has a different function to perform when embodied in the complete belt, the percentage or degree of stretch to which each is subjected will differ from the percentage 30 or degree to which the other are subjected.

That branch of my invention which is embodied in the method of producing this belt consists, essentially, in first fabricating the inner or compression member by mixing 35 with soft vulcanizable rubber, cotton, wool or other fiber, with the fibers positioned essentially crosswise of the sheet or strip; in fabricating the intermediate or central member by rubberizing a sheet or strip of cord fabric, with the cords lengthwise of the sheet or strip; in materially stretching such sheet or strip so that its stretchability, when it is embodied in the completed belt, will have been largely or substantially wholly eliminated; in fabricating the outer or tension member of rubberized fabric cut on the bias; in first winding this compression member on a forming drum or structure; in then winding such central member on the already wound 45 compression member; in winding such tension member on the already wound central

member; and finally in vulcanizing, as by steam heat, the material so fabricated and wound one upon the other.

The result of my invention in its two aspects is a driving belt which is substantially non-stretchable circumferentially; which, because of the construction referred to, notably the combined rubber and fibrous compression or inner member, will grip the 55 walls of any grooved pulley on which the belt is used, and which will readily bend and grasp the pulley surfaces without losing that effect by any material subsequent stretching, and yet will be firm and nearly rigid transversely.

In the accompanying drawings forming a part of this specification:

Fig. 1 is a diagrammatic view of a tension and winding apparatus used in carrying out 70 my method;

Fig. 2 is a view of a piece of fabric cut on the bias;

Fig. 3 is a like view of a piece of mixed vulcanized rubber and fiber, utilized in forming the inner or compression member of my belt;

Fig. 4 is a sectional view of a winding drum, its spool and a roll of belting thereon;

Fig. 5 is a side elevation of the belt complete; and

Fig. 6 is a sectional view of the belt showing the different members.

I will first describe my method because it results in the production of the belt. In this 85 way my invention will be more readily understood.

Referring first to the apparatus I prefer to employ in carrying out the stretching and winding steps of my method, the numeral 1 90 designates a roll upon which is wound, first, a quantity of material which is to comprise the compression member, and when this is consumed then a quantity of the material which is to comprise the central member, and 95 when this in turn is consumed, then a quantity of the material which is to comprise the tension member. Or there may be, say, three rolls, such as 1, each roll carrying a quantity of the respective materials and each roll in 100 turn mounted in the machine.

As shown in Fig. 1, the material to con-

stitute the compression member has already been wound on the spool carried by the drum, and the material constituting the central member is in the act of being wound on the 5 compression member, the winding being nearly complete, as usually three layers are sufficient. Later in the process the material comprising the tension member will be wound on the central member.

10 As illustrating the operation of the apparatus employed for winding and tensioning the materials it will be seen that the material comprising the central member, generally designated 2, passes over a guide roller 3, 15 a flattening platform 4, another guide roller 5 and a tension roller 6. The shaft 7 of this latter roller is put under different degrees of friction through a screw 8 and its friction block 9, to cause the roller 6 to revolve with 20 more or less resistance. In this way the required tension for the central and tension members is put upon the material as it is wound upon the spool on the drum.

A drum 10 having a gear wheel 11 is mounted 25 on a shaft 12 and rotated by an idler gear 13 driven by a driving gear 14 on the shaft 15 of an electric or other motor generally indicated at 16. On this drum is fitted a removable spool 17 as best seen in Fig. 4. The 30 materials are wound directly on this spool, which is carried by the drum, the spool being removable with them as a whole, as shown also in Fig. 4. A knife, which is utilized in cutting the roll of belting into the individual 35 belts forms another invention independent of this one and is the subject of an application for a patent filed by Amos Puterbaugh, June 19, 1922, Ser. No. 569,410.

It will now be seen that when the motor is 40 put in motion the several gears will rotate the drum with its spool, so that the different sheets or strips which constitute the respective members of the belt can be wound on the spool, in succession, and each sheet or strip 45 put under the required tension, as determined by the adjustment of the tension device, applicable to each sheet or strip.

Preceding the stretching and winding steps it will be understood that the material 50 for each belt member is fabricated. The compression member is fabricated by mixing soft vulcanizable rubber with fiber, preferably of cotton or wool. This mixing of the rubber and fiber is preferably performed by 55 a rubber mixing mill—a pair of rolls, one of which travels faster than the other. The body of rubber so mixed with the fiber is run through a calender machine which forms it into a sheet in which the fibers are found 60 to tend to position themselves lengthwise of the strip. After the sheet is formed it is cut off in strips crosswise of the sheet so that the fibers will stand crosswise of the strip. The effect of running the rubber sheet 65 through such calender machine is to deprive

it of any real stretchability lengthwise, but leave it unaffected crosswise. When therefore the strips are cut crosswise of the sheet, this lateral stretchability in the sheet becomes longitudinal stretchability in the 70 strips.

The central member is fabricated by taking a sheet or strip of cord fabric and rubberizing it in the well known way of rubberizing fabric. The strips are cut so that the cords run lengthwise the strip, sometimes called a straight or parallel cut.

The fabrication of the tension member is done by rubberizing a sheet of fabric cut on the bias, at say an angle of 45 degrees to the warp or lengthwise strands, which are crossed by the woof.

The characteristic of the compression member is yieldability as it bends round the pulley. The characteristic of the central member, besides extreme strength, is substantially non-stretchability due to the essential stretchability of the cord fabric having been taken out by the stretching operation which precedes the actual winding. The 85 characteristic of the tension member is also strength.

It will now be seen that my method consists in fabricating, substantially in the manner above described, the material for the inner or compression member, with its quality of yieldability; in fabricating the material for the central member, likewise in the way above pointed out, with its practically non-stretchable quality; in fabricating the material for the tension member, also in the manner pointed out, so that these two members will resist the tension they are put under in use; in subjecting the material of the central member to a tensioning or stretching operation and in winding the three elements, successively, on the drum, first winding the material of the compression member and properly uniting the ends of enough material to girth the spool; in then tensioning and 100 winding the material composing the central member with as many laps as desired, say three, which is preferable; and finally in winding the material of the tension member 110 again with as many laps as desired, preferably three.

When the belt has been thus formed and built up it is in the form of a roll of belting material, as best seen in Fig. 4. In this state it is vulcanized by the usual vulcanizing process employed in the manufacture of pneumatic rubber tires. The effect of the vulcanization is to cause the several members or zones, and the laps of material composing them, all to "run" together or unite to make a 120 finished and homogeneous structure.

Referring now to the belt that results from this method, attention is called to Figs. 5 and 6 where the same is illustrated in its complete condition, having been cut or severed 130

from the roll of belting on the spool. This belt so made has the compression member, the central member and the tension member, characterized by the fact that the compression member is compressible in respect to the rubber ingredient, while the central member is practically or substantially non-stretchable.

10 The subject matter of the method herein fully set forth is not claimed in the present case but is reserved to form the basis of another application with method claims which will be filed during the pendency of this present case.

15 Having thus fully described my invention, what I claim as new and desire to secure by Letters Patent, is:—

1. A driving belt comprising a compression member composed of rubber mixed with free fiber, a central member composed of rubberized cord fabric, and a tension member composed of rubberized fabric cut on the bias, the material of the central member being laid

on the compression member and that of the tension member on the central member. 25

2. In a driving belt structure, comprising a roll of belting consisting of a compression member, a central member and a tension member, the compression member formed of soft rubber mixed with free fiber, the central member 30 formed of rubberized cord fabric and the tension member formed of rubberized fabric, the whole united and comprising a roll of belting.

3. A driving belt comprising a central 35 member composed of rubberized cord fabric, a tension member composed of rubberized fabric cut on the bias, a compression member composed of a mass of free fiber interspersed in soft rubber, said fibers being so embedded 40 in the rubber as to permit the longitudinal expansion to restrict transverse compression of the compression member.

In testimony whereof, I affix my signature.

ABRAHAM L. FREEDLANDER.
